FLOOR CLIP

Oscar E. Rothfuchs, Michigan City, Ind., assignor
to Pullman-Standard Car Manufacturing Company,
Chicago, Ill., a corporation of Delaware

Application February 8, 1946, Serial No. 646,319

9 Claims. (Cl. 189—35)

1

This invention relates to floor securing devices of the general type utilized in railway cars for securing a wooden floor to a metallic underframe and adapted removably to secure such floors to the longitudinal members of the underframes without perforation of such members by the securing means.

The primary object of the invention is the provision of an improved floor clip of increased strength, adapted rigidly to apply the clamping pressures necessary to the proper installation of the wooden floors in railway cars without distortion under the pressure applied by the securing means.

Another object of the invention is to provide a floor clip for attachment of wooden floors to metal frame members in which the terminal portion of the clip engaging the floor is provided with inherent means penetrating the wooden floor to prevent rotation of the clip and having means for limiting such penetration.

An important object of the invention is the provision of a floor clip constructed from a metal blank of such section that upon formation of the clip, the prongs for penetrating the floor and the means for limiting such penetration are automatically formed as an integral part thereof. The floor clip is of such construction and so formed as readily to be fabricated upon automatic machines intended for the purpose, and adapted to be constructed, preferably, in a single operation.

The foregoing and other objects are attained by the arrangement illustrated in the accompanying drawings, in which

Fig. 1 is a general perspective view illustrating a wooden floorboard as used in railway box car construction, supported upon a Z bar stringer member of the metal underframe, with the floor clip of this invention in position to engage beneath the uppermost flange of the stringer member and upwardly offset terminal portion of the clip engaged against the underside of the floor, with the securing bolt and nut in position for insertion through the floorboard and clip at a point between the edge of upper flange of the stringer member and the offset portion of the clip;

Fig. 2 is a cross sectional view through a portion of a car floor showing the device as used in connection with a metal angle member to which the floor is secured, with the clip member engaged beneath the horizontal flange against which and the floor the clip is clamped by the securing bolt and nut, with the floor penetrating

2

prongs of the clip shown entered within the floor, and such penetration limited by the horizontal flange at this terminal portion of the clip;

Fig. 3 is a cross sectional view similar to Fig. 2 but showing the floor and securing clip member as applied in connection with a channel shaped underframe sill member in which the upper horizontal flange of the sill member is tapered and the floor clip correspondingly shaped to the same contour for engagement therewith without disturbing the normal engagement of the offset portion of the clip with the underside of the floor;

Fig. 4 is a detail plan view of one form of the floor clip of this invention in which the clip is formed from a commercial rolled channel member, and clearly revealing that formation of the clip whereby the cutting of the blank member forming the clip at one end provides the next adjacent clip with a correspondingly contoured end portion;

Fig. 5 is an end elevational view of a commercial channel type of floor clip illustrated in Fig. 4;

Fig. 6 is a detail plan view similar to Fig. 4 but illustrating the floor clip as constructed from a plate member pressed in the form of a channel from which the clip is fabricated, the clip shown being of the type for engaging a tapered flange of a supporting member as illustrated in Fig. 3; and

Fig. 7 is an end elevational view of the pressed metal floor clip illustrated in Fig. 6.

In the drawings, 10 represents a wooden floor member as used in railway box cars, and illustrated in Fig. 1 as supported upon a longitudinally extending Z-shaped stringer member 11. The floor is adapted to be secured to the stringer member by means of a clip member 12 engaging the underside of upper horizontal flange 13 of the stringer to clamp the flange between the clip and under surface of the floor by means of the pressure applied by a securing bolt 14 and lock nut 15. Any suitable type of lock nut may be used for the purpose. The floor clip 12 is of

channel shaped formation, as best shown in the detail illustrations represented in Figs. 4 to 7, and is applied with the flanges 16 of the clip directed upwardly to provide spaced engaging portions at one end of the clip in contact with the underside of the stringer member and similarly spaced engaging portions at the opposite end of the clip against the underside of the floor. These latter floor engaging portions, bearing cornerwise against the floor, are designed to penetrate the floor sufficiently to prevent the clip from rotating

about the bolt 14 as the lock nut 15 is tightened to draw the assembly to final position.

The floor clip, as best shown in Figs. 1 to 3, is constructed in one piece and is bent upwardly at 17 to provide the floor engaging portions having upwardly directed flanges with the end edges of the flanges perpendicular to the inclined web portion, and due to this upward inclination of the clip member, the flanges 16 are adapted, inherently, from the section used, to form upwardly directed corner portions providing prongs 18 which, bearing cornerwise against the underside of the floor, enter the floorboards when the securing nut 15 is tightened to prevent rotation of the clip during this operation. Penetration of the floor by the prongs 18 is limited through the medium of an integral flange 19 formed on the clip member at the time it is cut to length by providing the web portion 21 of greater length than the flanges 16 and disposing the flange thus formed horizontally for parallel engagement with the undersurface of the floor. In the installation of the clip, when this flange 19 comes in contact with the underside of the floor, it acts as a positive limit stop to any further penetration of the floor by the prong portion 18 so that additional tightening of the nut 15 will serve to apply greater clamping pressure on the underframe member more securely to fasten the floor relative to the underframe.

The clip member is provided with an opening 20 in its web portion 21 for the reception of the securing bolt 14, and to facilitate manufacture of the device in automatic machinery, the two ends of the clip, it will be noted, are of similarly shaped contour, so that where the projecting flange 19 is provided at the one end for limiting penetration of the rotation-preventing prongs 18 into the floor, the other end is provided with a recess 22 to the same inner contour as the outer contour of the flange 19 with the spaced flanges 16 affording the sole means of contact with the underside of the flange 13 on the stringer member. Thus it will be seen that in the manufacture of the clips from a metal blank of the proper cross section, a single cut finishes off the end of one clip and at the same time provides the finished end of the next adjacent clip. It is then necessary only to provide the bolt hole 20 and bend the clip to provide the upward inclination 17 and the horizontal disposition of the flange 19. All of this cutting of the clip, punching and bending, may be performed in a single operation by the use of suitable automatic machinery.

It will be noted that the bolt 14, passing through the floor 10, penetrates the clip member at a point outside the area of the flange 13 of the underframe member, but inwardly of the offset portion 17 of the clip, so that the full pressure to be applied by the bolt may be realized in the clamping pressure to be exerted by the floor clip against the flange 13 of the underframe member.

In Fig. 2, the clip is shown as applying clamping pressure on the horizontal flange of an angle member 23 forming part of the underframe structure to secure the floor 10 thereto. In this figure the function of the prongs 18 and that of the flange 19 is clearly revealed; the flange serving positively to prevent penetration of the prongs within the floor beyond the predetermined amount shown.

In Fig. 3, the clip is similar in its application to those shown in Figs. 1 and 2, but is provided with a downwardly inclined portion 24 at the terminal portion thereof adapted to engage the sloping

underside of the sill member 25. Provision of this additional inclined portion in the clip prevents undue canting thereof as the lock nut 15 is drawn up, and thereby insures proper engagement of the prongs 18 and the limiting flange 19 with the underside of the floor 10.

From the foregoing it will be seen that there has been provided a floor securing clip of channel formation having upwardly directed flanges 10 adapted at respectively opposite ends of the clip to engage an underframe member and to be imbedded in the underside of the floor, with means for limiting penetration of the floor; of simple design, and adapted readily for fabrication in 15 mass production by means of automatic machinery with a minimum of operations, and which is stronger than similar clips heretofore provided while retaining lightness of weight.

What is claimed is:

20 1. A floor clip comprising a channel shaped member having a web and upwardly directed flanges, said clip having an upwardly inclined portion having upwardly directed flanges with the end edges of said flanges perpendicular to the inclined web portion to form upwardly directed corner portions providing prongs, and a horizontally projecting flange member integral with the clip at the base of said prongs.

30 2. A floor clip comprising a channel shaped member having a web portion and upwardly directed flanges, said flanges at one end extending beyond the web of the channel member to provide one terminal portion of the clip and said web extending beyond the flanges at the other 35 end of the channel to provide the opposite terminal portion, a bolt opening in the web portion, said web and flanges extending from the first terminal portion beyond said bolt opening and having an upwardly inclined portion having upwardly directed flanges with the end edges of said flanges perpendicular to the inclined web portion to form upwardly directed corner portions providing prongs, and said web extending beyond the flanges being disposed substantially 40 parallel to the web adjacent the bolt opening.

3. A floor clip comprising a channel shaped member having a web portion and upwardly directed flanges, said flanges at one end extending beyond the web of the channel member to provide one terminal portion of the clip and said web extending beyond the flanges at the other 50 end of the channel to provide the opposite terminal portion, said flanges extending beyond the web being offset in a downwardly inclined direction, a bolt opening in the web portion, said web and flanges extending from the first terminal portion beyond said bolt opening and having an upwardly inclined portion having upwardly directed flanges with the end edges of said flanges perpendicular to the inclined web portion to form upwardly directed corner portions providing prongs, and said web extending beyond the flanges being disposed substantially 55 parallel to the web adjacent the bolt opening.

4. In a floor clip for securing together a sill and a floorboard supported thereby, a channel shaped member having a horizontally disposed web and vertically extending flanges, an opening 60 in the web for receiving a bolt to clamp the sill between said clip and floorboard, said clip having an upwardly inclined portion having upwardly directed flanges with the end edges of said flanges perpendicular to the inclined web portion to form upwardly directed corner 65 portions.

70 75

tions providing prongs, and means for limiting the penetration of said prongs into the floor.

5. A floor clip comprising a channel shaped member having a web and vertically disposed flanges, said clip having an upwardly inclined portion having upwardly directed flanges with the end edges of said flanges perpendicular to the inclined web portion to form upwardly directed corner portions providing prongs, and a horizontally disposed flange integral with the channel member at the base of said prongs.

6. A floor clip fabricated from a commercial rolled channel member comprising a horizontally disposed web and vertically disposed flanges, said clip having an upwardly inclined portion having upwardly directed flanges with the end edges of said flanges perpendicular to the inclined web portion to form upwardly directed corner portions providing prongs, and an offset portion of said web disposed horizontally at the 20 base of said prongs.

7. A floor clip fabricated from a pressed channel shaped plate member comprising a horizontally disposed web and vertically disposed flanges, said clip having an upwardly inclined portion having upwardly directed flanges with the end edges of said flanges perpendicular to the inclined web portion to form upwardly directed corner portions providing prongs, an an offset portion

15 10 of said web disposed horizontally at the base of said prongs.

8. A floor clip comprising a channel shaped member including a web and upwardly directed flanges, said clip being provided with an upwardly inclined portion having upwardly directed flanges with the end edges of said flanges perpendicular to the inclined web portion to form upwardly directed corner portions providing prongs, and a limit stop adjacent the base of said prongs.

9. A floor clip comprising a channel shaped member including a web and upwardly directed flanges and provided with an upwardly inclined portion having upwardly directed flanges with the end edges of said flanges perpendicular to the inclined web portion to form upwardly directed corner portions providing prongs.
